UNITED STATES PATENT OFFICE.

ARCHIBALD ALEXANDER MACINTOSH, OF ST. KILDA, AND WILLIAM HENRY HUNT, OF MELBOURNE, VICTORIA, AUSTRALIA.

APPARATUS FOR MAINTAINING PREDETERMINED PRESSURE CONDITIONS IN GAS-RETORTS.

1,329,129.

Specification of Letters Patent. Patented Jan. 27, 1920.

Application filed April 2, 1917. Serial No. 159,283.

To all whom it may concern:

Be it known that we, ARCHIBALD ALEXANDER MACINTOSH and WILLIAM HENRY HUNT, subjects of the King of Great Britain, residing at 15 Loch street, St. Kilda, and 340 Spencer street, Melbourne, respectively, in the State of Victoria, Australia, have invented certain new and useful Improvements in Apparatus for Maintaining 5 Predetermined Pressure Conditions in Gas-Retorts; and we do declare the following to be a full, clear, and exact description of the invention, such as will enable others skilled in the art to which it appertains to make 10 and use the same.

This invention has been devised to provide an apparatus calculated to maintain equilibrium or any predetermined condition of pressure in retorts or gas offtake pipes 20 from horizontal inclined or vertical gas making retorts from coke ovens chamber ovens or other apparatus of a like nature used in gas making.

The invention is also applicable for successful employment to retorts or ovens wherein the volatilization of other suitable substances is to be conducted and from which gases or volatilized mineral matters are produced.

In the past devices have been employed in the manufacture of gas, for instance, and known as retort house governors and their like having diaphragm governing bells balance or counter-balance weights; these have been aimed at maintaining an equilibrium of pressure in the foul gas mains, *i. e.* the mains in communication with the retorts, but in practice it has been found that such appliances do not satisfactorily fulfil the function 40 of maintaining an equilibrium or predetermined condition of pressure in the retorts or gas offtake pipes from the retorts or gas generators. We have found by experiment that by the use of our invention a satisfactory maintenance of an equilibrium or any predetermined condition of pressure is achieved with regularity and reliability in any individual retort or gas offtake irrespective of the predetermined condition of 45 pressure in any other retort or gas offtake even though common members of the same installation.

In order that our invention may be the

more easily understood, reference may be made to the accompanying sheet of drawings, in which—

The figure is an end elevation partly in cross section illustrating an apparatus as hereinafter described for carrying out our invention.

In this drawing it will be seen that in carrying out our invention we employ a gas tight vessel *a* constructed preferably of metal and designed somewhat after the vessel known generally in gas works practice 65 as a hydraulic main but we do not confine ourselves to any arbitrary size or shape of the vessel. This vessel *a* is divided into two chambers *a'* and *a''* by a division plate *b*. To the second chamber *a''* is attached a *T* 70 piece valve or other suitable connection *c* open to the atmosphere and inside of said *T* piece valve *c*, or other connection as mentioned, is fitted an adjustable threaded sleeve *d* which may be raised or lowered by screw 75 action by the thread *d'* the sleeve *d* being adjusted by a screw driver operating in an incision *d''* to regulate the height of the liquid at its normal line in both the chambers *a'* and *a''* in the vessel, *a*.

Into the first chamber *a'* is admitted the gas offtake pipe *e* from the retort the downwardly pointing extreme end of which when in operation is immersed in the liquid *f* in the said vessel, *a*. Attached to the top of 85 the vessel *a* in the first chamber *a'* is the leadaway foul gas main *g* the gases within same being subject to a vacuum, the action being that when any pulsations and abnormal suction take place in the leadaway foul 90 gas main *g* the liquid in the first chamber *a'* will rise proportionately in such chamber and enhance the depth of immersion by liquid *f* of the inlet pipe *e* leading from the retorts; the air, coming freely into the second 95 chamber *a''*, maintains a constant barometric pressure upon the surface of the liquid *f* therein and the screw-threaded sleeve *d* maintains the normal level of escapement of the liquid *f* from the vessel. A small inlet 100 pipe *h* is provided for the maintenance of the supply of liquid which is constantly running into the first chamber.

In some cases we may prefer to cause the pipe *h* to deliver its liquid supply in jets or 105 sprays into the upper portion of the offtake

pipe *e* so that the fluid may descend with the gas into the chamber *a'* and assist in cleansing the said offtake pipe *e*.

We do not confine ourselves to the depth 5 at which the division plate *b* may proceed downward in the liquid *f* and we reserve to ourselves the right, to also admit the air through an opening provided in the top of the second chamber *a²*, say for instance at 10 the dotted position *a⁴* to employ a perforated loose cover *a⁵* placed over it to keep dust from entering *a²*.

In operation the level of the liquid *f* in the second and first chambers *a²* and *a'* respectively is adjusted by raising or lowering 15 by screw action the adjustable sleeve *d* hereinbefore mentioned in order that there may be a constant stream of liquid flowing over into and escaping by the said adjustable 20 sleeve *d* (or valve) and as the air enters through the upper end *c'* of the *T* piece *c* (in the lower portion of which the sleeve *d* is set) the vacuum, which varies in the foul 25 gas exhauster main *g* will operate upon the water *f* in the first chamber raising or lowering, as the case may be, the said liquid therein and increasing or decreasing the depth 30 through which the foul gas in *e* from the offtake pipe of the retorts, is to travel before reaching the upper part *a'* of the first chamber *a* and proceeding from thence to the exhauster foul gas leadaway main *g*.

By the means we have described a constant equilibrium or any predetermined condition of pressure in the retorts or offtake 35 pipe leading from the retorts is automatically preserved.

In manufacturing gas from coal, the greatest volume of pure gas is obtained 40 when there is perfect equilibrium, that is a balanced pressure within and outside of the retort. By this, we mean that the pressure within the retort is equal to the pressure of the atmosphere. Under these conditions, a 45 *U* tube gage attached to the retort will show that the liquid therein is level, by being level in both limbs of the *U* tube. The reason why it is preferable to obtain and maintain this equilibrium, is to prevent the 50 escape of the gas through the cracks in the walls of the retort, by which the quantity of gas, tar, and ammonia recoverable from a given quantity of coal, would be reduced. The pressure of the gas in a hot retort above 55 atmospheric pressure, furthermore, causes a loss of gas, tar and ammonia, by overheating the gas, inasmuch as it then comes into contact with the hot walls of the retort with resultant decomposition of hydrocarbons and other ingredients of gas. In cases where 60 there is negative pressure in the retort, furnace gases and air will be drawn into the retort with the result that the gas therein is diluted with nitrogen and carbon dioxid, 65 and the air thus drawn into the retort may

cause combustion of the gases therein, resulting in a loss in their calorific value.

We would therefore have it understood that by the means we have before described we are enabled to employ without varying 70 the equilibrium or predetermined condition of pressure a varying condition of vacuum in the leadaway foul gas main *g* to induce a flow of gas from the generator or retort through the inlet pipe *e* the outflow being 75 controlled by a liquid bath as *f* in which the inlet pipe *e* is submerged, the depth of such submersion being automatically counterbalanced during the varying conditions of 80 vacuum (caused by the exhauster) by the admission of a pre-arranged and maintained supply of liquid *f* and the free inlet of air to the opposite side of a dividing plate or diaphragm as *b* in a water seal chamber 85 as *a'*.

i is a runaway tar pipe which at any convenient distance may join with the runaway pipe *d³* and which may be emptied of tarry matter from time to time by the usual means. Lids as *k* and *k'* for cleansing purposes may 90 be employed where shown so as to enable the workmen to freely use a tool in the direction required.

Preferably but not arbitrarily we would employ one of the complete sets as illustrated to each retort, but it is obvious that we may amplify the method and means we have hereinbefore explained by employing only one sleeve and open throat for the atmosphere to the outer side of a diaphragm 100 or dividing plate to a plurality of inlets as *e* and outlets as *g* in which case the one vessel with the sleeve and opened atmospheric throat would *de facto* fulfil the function of maintaining equilibrium or any predetermined condition of pressure to a plurality 105 of retorts or gas offtakes from retorts.

It will be obvious from a perusal of the drawings and description hereinbefore set forth that were a plurality of retorts employed to the one governing means as last aforesaid adjustment could be made for the varying conditions in any individual retort or gas offtake from retorts.

We claim as our invention:

1. An apparatus of the class described, comprising a receptacle adapted to contain a liquid and having two compartments connecting adjacent the bottom of the receptacle, an intake pipe leading into and extending below the liquid level in the first compartment of the receptacle, an outlet pipe leading from the first compartment of the receptacle, and a device associated with the said receptacle and adapted to admit air 120 to and permit the escape of liquid from the upper portion of the second compartment in the said receptacle, so that atmospheric pressure is maintained in both said compartments in the said receptacle. 130

2. An apparatus of the class described, comprising a receptacle adapted to contain a liquid and having two compartments connecting adjacent the bottom of the receptacle, an intake pipe leading into and extending below the liquid level in the first compartment of the receptacle, an outlet pipe leading from the first compartment of the receptacle, a device associated with the said receptacle and through which air is admitted to and liquid permitted to escape from the upper portion of the second compartment in the said receptacle, and means associated with the said device for regulating and determining the height at which the liquid escapes from the second compartment of the receptacle.

3. An apparatus of the class described, comprising a receptacle adapted to contain a liquid and having two compartments connecting adjacent the bottom of the receptacle, an intake pipe leading into and extending below the liquid level in the first compartment of the receptacle, an outlet pipe leading from the first compartment of the receptacle, a **T** pipe connected to said receptacle, through which air is admitted to and water permitted to escape from the second compartment in the receptacle, and an adjustable sleeve in said **T** pipe for determining the height at which the water in the receptacle is permitted to escape.

termining the height at which the water in the receptacle is permitted to escape.

4. An apparatus of the class described, comprising a receptacle, a partition wall extending downwardly into the receptacle to a point adjacent the bottom thereof, so as to divide the interior thereof into two compartments communicating with one another beneath the lower edge of the said partition wall, an intake pipe leading into and extending below the liquid level in the first compartment of the receptacle, an outlet pipe leading from the first compartment of the receptacle, means for admitting liquid to the said first compartment of the receptacle, a **T** pipe connected to said receptacle, through which air is admitted to and water permitted to escape from the second compartment in the receptacle, and an adjustable sleeve in said **T** pipe for determining the height at which the water in the receptacle is permitted to escape.

In testimony whereof we have signed our names to this specification in the presence of two subscribing witnesses,

ARCHIBALD ALEXANDER MACINTOSH.

WILLIAM HENRY HUNT.
